United States Patent Office.

JOHN HARTMAN, JR., OF PHILADELPHIA, PENNSYLVANIA.

Letters Patent No. 64,314, dated April 30, 1867; antedated October 30, 1866.

IMPROVEMENT IN SKATES.

The Schedule referred to in these Letters Patent and making part of the same.

TO ALL WHOM IT MAY CONCERN:

Be it known that I, JOHN HARTMAN, Jr., of the city and county of Philadelphia, and State of Pennsylvania, have invented a new and useful Improvement in Skates; and I do hereby declare that the following is a full and exact description thereof, reference being had to the accompanying drawings, and to the letters of reference marked thereon.

The nature of my invention and improvement consists in a novel mode of adjusting and fastening the skate to the boot, which will be understood by the following description. In the accompanying drawings, which make a part of this specification—

Figure 1 is a top view or plan of the improved skate.

Figure 2 is a vertical longitudinal section of same.

Figure 3 is a view of the skate inverted.

Figures 4 and 5 are a face and edge views of the swivel clamping-plate F'.

Figures 6 and 7 are similar views of the supplementary plate D.

Like letters in all the figures indicate the same parts of the improved skate.

A is the runner of the skate, which is secured to the sole B in the usual manner. C is the front or toe strap, to the upper side of which, beneath the sole B, I attach a supplementary plate, D, which is provided with a tightening screw, E. The said screw works in the boss a, and the pin b turns freely in the sole B, it being provided with a rivet-plate, c, as seen in figs. 1 and 2. The said plate D is secured to the strap C by means of the rivets d d. The said strap may be buckled so as to allow the toe of the boot to be freely put in place and remain so, it being always tightened and loosened by operating the set-screw E before described. In tightening said strap the swivel-clamping plates F and F' are borne against by the strap so as to bring their upper projecting ears e e and e' e' on the heel and toe parts of the plates to bear against the heel and sole of the boot, the plates turning freely on the fulcrum-pin G, which is adjustable by means of the longitudinal slots f in the plates and sole B. Then the said plates are confined to the sole so as to take the strain off of the strap C by means of the screws H H, which pass through the concentric slots g g. When the plates are once adjusted so as to bring the runner A central with the foot, one of the screws H may remain tight. In the adjustment of the clamping-plates F and F' the nut h on the fulcrum-pin G should be perfectly loose, so as to allow the pin to find its proper position in the slots f. I is the heel-strap, constructed and arranged in the ordinary manner.

Having thus described my improvement, what I claim as new, and desire to secure by Letters Patent, is—

1. Tightening the skate by means of a supplementary plate, D, operated by a screw, E, substantially in the manner above described.

2. The combination and arrangement of the swivel-clamping plates F and F', with the sole B, by means of the adjustable fulcrum-pin G, substantially in the manner and for the purpose above set forth.

In testimony that the above is my invention I have hereunto set my hand and affixed my seal this 29th day of September, 1866.

JNO. HARTMAN, JR. [L. S.]
